(57) **CLAIM**

We claim the ornamental design of the putting trainer for golf, as shown.

DESCRIPTION

FIG. 1 is a perspective view from the right front quarter showing our design for a putting trainer for golf;

FIG. 2 is a perspective view of the left side on the transverse axis; the right side view is identical;

FIG. 3 is a perspective view of the front on the longitudinal axis;

FIG. 4 is a perspective view of the rear on the longitudinal axis;

FIG. 5 is a perspective view from the left front quarter; and, FIG. 6 is a perspective view from the left rear quarter.
